UNITED STATES PATENT OFFICE.

EDWARD D. FLINT, OF OAKLAND, CALIFORNIA.

DESIGN FOR A HORSESHOE-PAD.

SPECIFICATION forming part of Design No. 30,095, dated January 31, 1899.

Application filed December 30, 1898. Serial No. 700,769. Term of patent 14 years.

To all whom it may concern:

Be it known that I, EDWARD D. FLINT, a citizen of the United States, residing in Oakland, county of Alameda, State of California, have invented and produced a new and original Design for a Horseshoe-Pad, of which the following is a specification, reference being had to the accompanying drawings, forming a part thereof.

Figure 1 is a perspective view looking toward the bottom of the pad. Fig. 2 is a perspective view looking toward the upper side of the pad.

My design comprises two essentially flat sides A, having convex outward peripheries B, with the front end connected by an essentially straight line C, the rear ends curved inwardly and merging into a continuous concaved outline D. Between the front edge C and the front of the concavity is a depression E in the upper surface, as shown.

The lower front portion of the pad is thickened to form an elevated table, as shown at F, the front edge of which coincides with the front edge of the part A, and the rear end is continuous around and coincident with the front of the segmental opening D. The sides are convex and essentially concentric with the outer periphery of the plate A. The lower surface of the thickened portion F is formed with semiglobular indentations G.

Having thus described my invention, what I claim as new, and desire to secure by Letters Patent, is—

The design for a horseshoe-pad or similar article substantially as shown and described.

In witness whereof I have hereunto set my hand.

EDWARD D. FLINT.
